UNITED STATES PATENT OFFICE.

LLOYD JONES, OF PITTSBURGH, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

METAL-WORKING MACHINE.

Application filed April 3, 1920. Serial No. 370,923.

To all whom it may concern:

Be it known that I, LLOYD JONES, a citizen of the United States, residing at Pittsburgh, Allegheny County, Pennsylvania, 5 have invented a new and useful Improvement in Metal-Working Machines, of which the following is a full, clear, and exact description.

The present invention relates to metal 10 working machines of the type adapted to operate on metal strips or bars in multiple.

The principal object of the present invention is to provide a mechanism automatically cooperating with a multiple metal 15 shearing device, superimposing and piling the metal as it is sheared thereby.

Another object of the present invention is to provide a machine for cutting or shearing metallic strips or bars in multiple into 20 substantially uniform lengths, and then pile the lengths one on top of the other.

A further object of the present invention is to take metallic strips or bars lying side by side and automatically superimpose and 25 pile the same after the performance thereon of an intermediate operation.

A still further object of the invention is to provide means for forming a plurality of stacks or piles of lengths of metallic 30 strips or bars on a carrier, facilitating transportation thereof to any desired point or points.

The foregoing and other objects, together with their attendant advantages, will be 35 apparent as the invention becomes better understood by reference to the accompanying specification and drawings forming a part thereof, it being premised that changes may be made in the various details and the 40 manner of operation within the scope of the appended claims without departing from the spirit of the invention.

Figure 1 is a top plan view largely diagrammatical of a shearing mechanism and 45 roller table feed therefor, illustrating a portion of the superimposing mechanism.

Figure 2 is a top plan view corresponding to Figure 1, of the piling mechanism.

Figure 3 is a side view of the mechanism 50 illustrated in Figure 1, showing the gauge for the shearing mechanism applied thereto.

Figure 4 is a side view illustrating the operation of a portion of the piling mech- 55 anism.

Figure 5 is a side view of the mechanism 55 illustrated in Figure 2, and

Figures 6 and 7 are enlarged detail views of the adjusting device for the piling mechanism.

At the present time it is customary to design metal working machines especially adapted to shear to lengths flat bars or strips in multiple, the number of the bars or strips ranging usually from two to eight depending upon the length of the shear 60 knife and the width of the bars or strips being operated upon. It is the purpose of the present invention to provide a superimposing and piling mechanism cooperating with the shearing mechanism described, for 65 automatically taking the bars or strips as they are cut into lengths and superimposing and piling the same.

Referring more particularly to the drawings, I have illustrated diagrammatically a 75 shearing mechanism 2 of the vertical type, adapted to receive a plurality of bars or strips from the feed rolls 4. These bars or strips are ordinarily received from a storage table on which they lie side by side, so that 80 they are fed to the shear mechanism in multiple, the number depending upon the width of the bars or strips and the capacity of the shearing mechanism. For this operation it will be apparent that the type of 85 shear is immaterial, any standard design being equally well adapted for the objects of this invention.

Cooperating with the shear mechanism is a roller feed table 5 and a suitable gauge 5^a 90 adjustable to any desired position along the frame 5^b. The gauge is preferably of a well known type so constructed that it is automatically released when the shear commences to operate. The lengths of bars are 95 delivered by feed rolls 5 to the superimposing rolls 6. According to the present invention, the feed rolls 5 are of a well known type having a substantially uniform diameter throughout the length thereof, while 100 the superimposing rolls 6 are so constructed that a portion of the operating surface adjacent one end lies in a higher plane than the supporting surface adjacent the other end, whereby the lengths of material at one 105 side thereof are lifted to permit superimposing the same on the lengths lying in a lower plane. As illustrated, the superim-

- posing rolls may be provided with steps 7 of gradually increasing diameter, or they may have conical portions 8 formed thereon. Cooperating with the enlarged portions 5 of the superimposing rolls are guides 9 adapted to push the lengths carried thereby laterally on top of the lengths carried by the smaller portions 10 of the rolls and into engagement with the piling stops 11.
- 10 It will be apparent that the mechanism just described operates to take bars or strips delivered in multiple in a side by side position or relation and superimpose the same into piles or stacks. These stacks pass in 15 turn from the superimposing mechanism to the piling mechanism over a suitable feeding device 12 and through the usual type of adjustable pinch rolls 14.
- I have illustrated the piling mechanism 20 as comprising a truck 15 adapted for longitudinal movement on the trackways 16 when brought into alignment therewith by the transversely operable transfer table 17. The lengths 18 of the strips or bars may be 25 supported on a surface 19 formed on the truck 15. Cooperating with the supporting surface on the truck is a pair of piling guides 20, having their lower edges shaped to conform to said surface so that they may rest 30 in engagement therewith during the piling operation. These guides may be provided with an adjustable stop 21 adapted to limit the travel of the lengths 18 when fed to the supporting surface by the pinch rollers 14.
- 35 After a pile of lengths of the desired height has been formed on the truck, the guides 20, which are carried by any suitable type of counter-weighted mechanism 22, are raised by drawing down a piston in the cylinder 40 24, which piston has a connection 25 with one end of the counter-weighted mechanism 22. With the guides raised as illustrated more particularly in Figure 5, the carrier 17 may be moved laterally to the desired 45 distance to permit the formation of a new pile on the supporting surface 19 of the truck 15. This operation may be repeated until the desired number of piles are formed on the truck.
- 50 In order to accommodate bars or strips of different widths, it is necessary that the guides 20 be adjustable toward and from each other. For this purpose I have provided adjacent each end of the guides a 55 transversely extending slotted bar 26, held in position on each of the guides by suitably formed angle members 27, and clamped in adjusted position by means of the through bolt 28 and clamping nut 29.
- 60 The advantages of the present invention arise from the provision of means for automatically taking bars or strips in multiple, occupying a side by side relationship, cutting the same into any desired lengths, and 65 then superimposing the lengths to form

piles or stacks which may be readily transported to any desired point or points.

I claim:

1. In a metal-working machine for strips, a roller feed table having a plurality of feeding rolls of substantially uniform diameter and a plurality of superimposing rolls of varying diameters for raising the strips to different levels to stack the same; substantially as described. 70

2. In a metal-working machine for strips, a roller feed table having a plurality of feeding rolls of substantially uniform diameter, and a plurality of superimposing rolls increasing in diameter throughout a portion of the length thereof for raising the strips to different levels to stack the same; substantially as described. 80

3. In a metal-working machine for strips, a roller feed table having a plurality of feeding rolls of substantially uniform diameter, and a plurality of superimposing rolls having their supporting surfaces at one end in a higher plane than their supporting surfaces at the other end for raising the strips to different levels to stack the same; substantially as described. 85 90

4. In a metal-working machine for strips, a plurality of superimposing rolls having a larger cross-section at one end than the other for lifting successive strips to progressively higher levels to permit superpositioning thereof; substantially as described. 95

5. In a metal-working machine for strips, a plurality of superimposing rolls having a larger cross-section at one end than the other for lifting successive strips to higher levels for stacking the same, means for feeding lengths thereto in multiple, and guides cooperating therewith for moving said lengths laterally into superimposed relation; substantially as described. 100 105

6. In a metal-working machine for strips, a plurality of superimposing rolls having a larger cross-section at one end than the other for lifting successive strips to higher levels for stacking the same, means for feeding lengths thereto in multiple, guides cooperating therewith for moving said lengths laterally into superimposed relation, and stops limiting the lateral movement of said lengths; substantially as described. 110 115

7. A piling mechanism for metal-working machines, comprising a supporting truck, guide members adjustably cooperating with the truck, and means for feeding superimposed lengths of material to the portion of the truck between said guide members; substantially as described. 120 125

8. In a metal-working machine for strips, a roller feed table having a plurality of rolls provided with surfaces at varying heights and guiding means co-operating 130

therewith for automatically superimposing said strips as they pass along said table, substantially as described.

9. In a metal-working machine for strips, 5 a roller feed table having a plurality of feed rolls and a plurality of surfaces at different elevations and co-operating guides for raising said strips to different levels to stack the same as they move along said 10 table, substantially as described.

10. In a metal-working machine for strips, a roller feed table having a plurality of feed rolls and a plurality of moving surfaces at different elevations and co-operating 15 guides for raising said strips to different levels to stack the same as they pass along said table, substantially as described.

11. In a metal-working machine for strips, a roller feed table having a plurality 20 of feed rolls, means for automatically superimposing said strips as they pass along said table, and means for receiving a plurality of stacks of said strips side by side, substantially as described.

25 12. In a metal-working machine for strips, a roller feed table having a plurality of feed rolls and a plurality of surfaces at different elevations and co-operating guides for raising said strips to different levels to 30 stack the same as they pass along said table,

and means for receiving a plurality of stacks of said strips side by side, substantially as described.

13. In a metal-working machine for strips, a roller feed table having a plurality 35 of feed rolls and a plurality of moving surfaces at different elevations and guiding means co-operating with said surfaces for superimposing said strips as they pass along said table, and means for receiving 40 a plurality of stacks of said strips side by side, substantially as described.

14. In a metal-working machine for strips, a roller feed table having a plurality of feed rolls, means for automatically superimposing 45 said strips as they pass along said table, means for receiving a plurality of stacks of said strips side by side, and means for rotating said feed rolls, substantially as described. 50

15. In a metal-working machine for strips, a roller feed table having a plurality of feed rolls of uniform diameter and a plurality of surfaces at different elevations for superimposing said strips as they pass 55 along said table, and power means for operating said feed rolls.

In testimony whereof, I have hereunto set my hand.

LLOYD JONES.
